LAWN SPRINKLER

Norris Nordenstam, Riverside, Calif.

Application September 18, 1950, Serial No. 185,381

7 Claims. (Cl. 299—71)

1

The present invention relates to an improved lawn sprinkler of the type described in my co-pending patent application Serial No. 23,249, now Patent No. 2,597,366, filed April 26, 1948. The present invention contemplates a water operated motor for oscillating a pair of sprays, the motor being operated by the water which ultimately passes through the sprays.

An object of the present invention is to provide an improved sprinkler of this type for use in sprinkling lawns characterized by the fact that it is rugged, simple, foolproof, inexpensive and of a minimum number of parts which are not likely to become worn in use.

Another object of the present invention is to provide a sprinkler comprising a minimum number of parts which may be made and assembled in accordance with present mass production methods.

Another object of the present invention is to provide an improved lawn sprinkler of this type characterized by the fact that it incorporates a novel valve of simple, rugged, foolproof construction which is automatically operated in accordance with the angular positions of the oscillating sprays.

The features of the present invention which are believed to be novel are set forth with particularity in the appended claims. This invention itself, both as to its organization and manner of operation, together with further objects and advantages thereof, may be best understood by reference to the following description taken in connection with the accompanying drawings in which:

Figure 1 is a top plan view of an improved lawn sprinkler embodying the present invention.

Figure 2 is a view in side elevation of the same and shows the spray heads at their extreme ranges of travel in dotted lines.

Figure 3 is a sectional view taken substantially on the line 3—3 of Figure 2.

Figure 4 is a sectional view on the line 4—4 of Figure 3.

Figure 5 is a view similar to Figure 4 but shows the parts of the sprinkler in a different operating position.

The sprinkler is mounted on a circular base 10 which supports the vertically extending water supply pipe 11, the lower end of the pipe 11 being received in an elbow fitting 12 which is welded to the circular base 10. The upper end of the pipe 11 as shown in Figures 1 and 3 is received in the elbow 13. The other opening of the elbow 13 receives the tube 15 having its other end closed

2

by the plug 16 welded or soldered therein. This tube 15 is provided with an annular flange 15A and 15C and a downwardly extending apertured portion in the frame of a nozzle 15B. It is noted that each of the elements specifically described above always remains stationary, these stationary elements being the elements 10, 11, 13 and 15 with its flanges 15A, 15C and nozzle 15B. The tube 15 rotatably supports the oscillatable housing or casing 17 which is in the form of an apertured ellipsoid. The casing 17 has a pair of alternately aligned water outlet tubes 18, 19 received in the wall of the casing and in communication with the hollow internal portion of the casing 17. The extreme ends of these tubes 18, 19 have mounted thereon correspondingly apertured spray heads 18A, 19A. If desired the casing 17 may have a plurality of apertures 17A therein to allow escape of the water as a spray therefrom to supplement the spray issuing from the heads 18A, 19A.

As shown in Figure 3 the casing 17 in fact comprises two interconnected parts 17B, 17C, these parts being joined together through a cooperating screw threaded connection 17D. In assembling the casing 17 on the stationary tube 15 the casing half 17C is slipped over the end tube 15 to contact the flange 15A as shown in Figure 3. Then, with the annular flexible gasket ring 22, coil compression spring 23 and annular ring 24 mounted on the tube, the other casing half 17B is slipped over the plug end of tube 15 and screwed into the cooperating casing half 17C. While these two casing halves 17B and 17C are being screwed together the coil compression spring 23 and flexible gasket material 22 is compressed so that a good fluid-tight connection is made between the two casing halves 17B, 17C and the stationary tube 15 on which it rotates.

In this respect it is noted that the coil compression spring 23 tends to move the composite casing 17 to the right in Figure 3 against the annular flange 15A as well as to resiliently press the ring 24 into engagement with the casing half 17B; and, the annular flexible gasket 22 which covers the spring 23 serves to prevent leakage of the water past the spring 23 and between the tube 15 and ring 24.

An important feature of the present invention is the valve construction shown in greater detail in Figures 4 and 5, such valve construction including the pivotally mounted valve element or flapper 30 which is pivotally mounted on the stationary pivot pin 31 secured to the inner boss 17E of the composite casing 17. This valve ele-

ment or flapper 30 cooperates with the nozzle 15B so as to alternately place such nozzle 15B in communication with the laterally extending tubes 17 and 19 in the resulting oscillatory movement of the casing 17.

Examining Figures 4 and 5, the pivoted valve element 30, due to gravity forces acting thereon, blocks off the opening to one of the tubes 18, 19. It is noted that while it is theoretically possible for the valve element 30 to assume a midposition in which neither the opening to tube 18 nor the opening to tube 19 is closed thereby, as a practical matter, such midposition is a relatively unstable one and any slight unbalanced force acting on such valve element, resulting from jar, inertia forces, or unbalanced forces developed during initial water flow, etc., causes the element 30 to be moved by gravity forces acting thereon to one of the valve closing positions. The entrance to tube 19 is shown blocked off in Figure 4. The water under pressure streaming through the nozzle 15B is always open to cause the interior hollow portion of the casing 17 to be filled with water. The water in the interior of casing 17 may emerge through the series of apertures 17A therein but a portion of the water flows into tube 18. The resulting reaction of the water leaving the nozzle 18 serves to pivot the casing 17 in the counterclockwise direction indicated by the arrow 33. Such counterclockwise rotation continues until the parts assume their full line positions shown in Figure 5. When this condition exists as shown in Figure 5 the pressure of the water emerging through the nozzle 15B now impinges on the pressure face 30A of the valve element 30 to cause the valve element 30 to move to its dotted line position shown in Figure 5 when the entrance to tube 18 is closed off and the entrance to tube 19 is opened. Thus, the water then flows out through the tube 19 and out of the head 19A at which point the reaction forces cause the casing 17 to rotate in the clockwise direction as indicated by the arrow 34 in Figure 5. Such clockwise rotation continues until the other pressure face 30B is moved into aligned position with the nozzle 15B in which case the water pressure acting on the face 30B causes the valve to be actuated, now to close off the opening to the tube 19 and to allow water to flow into the tube 18. This cycle continues with a resulting oscillation of the casing 17 and tubes 18, 19 carried thereon.

While essentially the valve element 30 is moved by water pressure, a certain amount of its motion is attributed to the fact that the valve element 30 strikes the tube nozzle 15B at the end of travel of the sprinkler head with the resulting impact imparting reverse movement to the valve element. For this purpose the pressure faces 30A and 30B are so shaped that they engage the valve element 30 at the ends of sprinkler head travel. Specifically, the pressure faces 30A and 30B, while essentially flat at regions thereof closest to the pivot pin 31, such faces are inclined more to the vertical at regions more remote from the pivot pin 31 to effect the aforementioned contact. This feature is of importance, particularly where the water pressure is low and may be insufficient in itself to cause the valve element 30 to flip over from one of its extreme positions to the other one of its extreme positions.

While the particular embodiments of the present invention have been shown and described, it will be obvious to those skilled in the art that changes and modifications may be made without

departing from this invention in its broader aspects and, therefore, the aim in the appended claims is to cover all such changes and modifications as fall within the true spirit and scope of this invention.

I claim:

1. In a sprinkler of the character described, a relatively stationary tube, a downwardly extending nozzle in communication with said tube, a casing pivotally supported on said tube and having a pair of radially extending water outlet tubes, a gravity actuated valve element pivotally mounted on said casing about a horizontal axis passing through a centrally located portion of said valve element and effective alternately to place said water outlet tubes in communication with said nozzle, said valve element being disposed below said nozzle with the axis of said nozzle passing through said horizontal axis when said casing is in a central position and said valve element having a pair of water pressure faces alternately moved into aligned position with said nozzle so that water from said nozzle impinges directly on said pressure faces to effect operation of said valve element.

2. In a sprinkler of the character described, an oscillatable casing having a pair of water outlet tubes extending radially thereof in alignment, a pivoted gravity actuated valve element movable between extreme positions for alternately closing off the entrance to one of said tubes and allowing communication between the interior of said casing with the other of said tubes, means pivotally mounting said valve element about a horizontal axis which extends through a central portion of said valve element, a tube assembly supporting said casing, a nozzle associated with said tube and in communication therewith, said valve element having a pair of water pressure surfaces alternately moved into alignment with said nozzle at the extremities of movement of said casing so that water from said nozzle impinges directly on said pressure faces to effect operation of said valve element.

3. In a sprinkler of the character described, a water inlet tube, nozzle means on said tube and in communication with said tube, casing assembly mounted on said tube, a V-shaped valve element pivotally mounted at its apex to said casing, a pair of aligned water outlet tubes extending radially of said casing and in communication with the interior thereof, the ends of said V-shaped valve elements being adapted to alternately close off the opening to one of said tubes while allowing water to flow through the opening of the other one of said tubes, said valve element having a pair of pressure surfaces on opposite legs of its V which are movable alternately into an aligned position with said nozzle means to effect operation of said valve element.

4. In a sprinkler of the character described, a water inlet tube having an associated nozzle, an oscillatable casing mounted on said tube, a pivotally mounted gravity actuated valve element on said casing, means pivotally mounting said valve element for movement about a horizontal axis which extends through a central portion of said valve element, said nozzle means being directed toward said central portion when said valve element is in a position midway between its extreme positions of travel, a pair of outlet tubes extending radially from opposite sides of said casing and in communication with the interior thereof, said valve cooperating with said tubes to block off the flow of water to one of said tubes while simulta-

neously allowing flow of water to the other of said tubes, said valve having a pair of water pressure surfaces movable at the extremities of its travel alternately into aligned position with said nozzle means so that water from said nozzle impinges directly on said pressure faces to effect operation of said valve element.

5. In a sprinkler of the character described, a stationary base, a water inlet tube mounted on said base with the upper end thereof extending generally horizontally, said tube end having a pair of spaced flanges thereon and nozzle means, a casing assembly mounted on said tube end, said casing comprising two screw threaded halves, one of said casing halves having an internal flange cooperating with one flange of said tube end, a coil compression spring encircling said tube end and having one of its ends in engagement with the other one of said tube end flanges, an annular ring on said tube end and abutting the other end of said coil compression spring, said other casing half having an inner annular flange in engagement with said ring, an annular ring of flexible material abutting said other tube end flange and said ring and enclosing said coil compression spring, a pair of aligned water outlet tubes extending radially from opposite sides of said casing, a V-shaped valve element pivotally mounted at its apex to said casing, the ends of said V-shaped valve element cooperating with the ends of said outlet tubes to alternately open and close ingress to the same, said V-shaped valve element having a pair of pressure surfaces automatically movable at the extremities of its travel into aligned position with said nozzle means to effect

35

operation of said valve element, the outer extremities of said water outlet tubes having reaction type spray heads.

6. The arrangement set forth in claim 1 in which said pair of pressure faces each have a portion thereof engageable with said nozzle at the extremities of travel of said nozzle to effect movement of said valve element.

7. In a sprinkler of the character described, a relatively stationary tube, a downwardly extending nozzle in communication with said tube, a casing pivotally supported on said tube and having a pair of radially extending water outlet tubes, a gravity actuated valve element pivotally mounted on said casing below said nozzle and effective alternately to place said water outlet tubes in communication with said nozzle, means pivotally mounting said valve element for pivotal movement about a horizontal axis which extends through a central portion of said valve element, said nozzle contacting said valve element at the ends of travel of said nozzle to effect movement of said valve element.
